UNITED STATES PATENT OFFICE.

ROBERT S. NOAH, OF ANNAPOLIS, MARYLAND, ASSIGNOR TO CLARENCE A. BEARDMORE,
OF ANNE ARUNDEL COUNTY, MARYLAND.

TIMER FOR INTERNAL-COMBUSTION ENGINES.

1,175,901.

Specification of Letters Patent. Patented Mar. 14, 1916.

Application filed April 26, 1915. Serial No. 23,918.

To all whom it may concern:

Be it known that I, ROBERT S. NOAH, a citizen of the United States, residing at Annapolis, in the county of Anne Arundel 5 and State of Maryland, have invented new and useful Improvements in Timers for Internal-Combustion Engines, of which the following is a specification.

This invention relates to timers or distributors for internal combustion engines, particularly those of the multiple cylinder type, the object of the invention being to produce a special form of distributor body having an arm in which the ignition wires 10 are collected and through which they are passed and connected at their inner ends to the contact segments, the arrangement being such that the distributor body may be rocked back and forth to advance and retard the spark without the ignition wires being displaced or without any interference between said wires and other adjacent parts of the machine, thus obtaining a distributor body and timer which is certain in operation and 15 reliable at all times.

With the above and other objects in view, the invention consists in the novel construction, combination and arrangement of parts, as herein described, illustrated and claimed.

In the accompanying drawings:—Figure 1 is an outside face view of the distributor body showing the relation of the same to the gear case of an engine. Fig. 2 is an enlarged inside face view of the distributor body. Fig. 3 is a detail longitudinal section of the revolving contact arm. Fig. 4 is a vertical longitudinal section through the distributor body, showing one of the wires and its relation to the arm and body of the distributor. Fig. 5 is a longitudinal section through the distributor taken at right angles to Fig. 4. Fig. 6 is a section on the line 6—6 of Fig. 4. Fig. 7 is a section taken on the same line as Fig. 6 showing the main body of the distributor formed in one piece. Fig. 8 is an inside face view of the construction shown in Fig. 7, indicating by dotted lines the arrangement and location of the wire receiving passages.

Referring to the drawings, in order to illustrate the application of the timer or distributor of this invention to an internal combustion engine, 1 represents what is known as the gear case usually arranged at 55 the front end of an engine as used in auto-

mobile practice, 2 designating the crank shaft, 3 the oil receiving neck or funnel, 4 the closing cap therefor, and 5 the spring for holding the timer or distributor in place relatively to the end of the timer shaft 60 (not shown), the spring 5 being pivotally mounted at 6 and the free end thereof being formed with an inwardly extending hemispherical projection 7 which is normally received in a concaved pocket or recess 8 in 65 the distributor body for the purpose of holding said body in its operative position, while permitting said body to be oscillated or partially turned to one side or the other by means of the operating connection 9 in order 70 to advance and retard the spark.

In the preferred embodiment of this invention, the main body of the distributor is cylindrical in shape, said body being indicated generally at A and comprising a main 75 section 10, a channeled section 11 and a cupped section 12. The cylindrical body of the distributor as a whole is provided with a radially extending arm 13 through which the ignition wires pass as will hereinafter 80 be described. The main section 10 is provided with a circular recess 14 to receive the adjacent face of the channeled section 11 and is also rabbeted as shown at 15 to receive the correspondingly rabbeted periphery of the channeled section 11. The section 11 is also rabbeted at 16 to receive the reduced inner peripheral portion of the cupped section 10. The sections 10, 11 and 12 may be glued or cemented together or 85 otherwise fastened together in fixed relation to each other.

The section 12 is provided with an internal flange 17 recessed to receive contact segments 18 of any suitable metal such as 95 brass, the exposed faces of the segments 18 being flush with the side face of the flange 17. Each of the segments 18 is fastened in place by means of a screw 19 and to the head of said screw is fastened by solder or 100 in any other way one of the wires as shown in Fig. 6, the extremity of the wire being preferably inserted in the slot of the screw head and soldered permanently therein.

In order to make room for the heads of 105 the screws 19 and the wires connected thereto, the member 11 is provided with the annular channel 20. In its opposite face the member 11 is provided with another annular channel 21 to receive the wires 23, four 110

of which are shown in Fig. 5, thus adapting the distributor body as illustrated in the accompanying drawings for use in connection with a four cylinder engine.

- 5 By reference to Figs. 4 and 5 it will be observed that the arm 13 is bored lengthwise to form a series of substantially parallel passages 24 for the wires 23, said passages extending lengthwise of the arm 13
 10 which may be of any desired length, preferably long enough as shown in Fig. 1 to extend above the gear case 1. Tubular ferrules 25 are inserted tightly in the outer ends of the passages 24 and around the wires 23
 15 which are headed or expanded and flattened against the outer extremities of the ferrules as shown at 26. The usual jacks 27 are adapted to be slipped over the plugs or stems formed by the ferrules 25 in the manner shown in Fig. 1, said jacks being fastened to the extremities of the ignition wires
 20 28 leading to the spark plugs or other igniters of the engine.

28 designates a rotary contact arm having a sleeve like hub portion 29 which is fastened to the timer shaft (not shown). Adjacent to its extremity the arm 28 is formed with a socket 30 to receive a slidable brush 31 usually formed of carbon, said 30 brush being urged outwardly by means of a backing spring 32 which thereby operates to hold the extremity of the brush 31 always in contact with the adjacent face of the flange 17 and the contact segments 18
 35 hereinabove described.

Instead of forming the main body of the distributor in sections as above described, the said body may be formed in one piece as shown at 33 in Fig. 7. In such case, 40 relatively long screws 34 are employed to fasten the contact segments 35 to the internal shoulder or bearing face 36. Holes 37 are bored through the arm 38 of the distributor body, certain of said holes having 45 angular portions 30 so that the wires when inserted through said holes may lead to their respective contact segments 35. Other holes 40 are bored at right angles to the holes 37 and 38 so as to enable the screws 50 38 to be inserted and also to enable the terminals of the wires 23 to be fastened to the heads of said screws. After this is done, plugs 41 are driven into the holes 42

and the entire device given a coat of varnish or the like.

It will of course be understood that the distributor including the main body thereof and the projecting arm, is composed of suitable insulating material such as fiber board or the like now in common use. In this 60 way the wires, although each separately insulated as shown at 42, are insulated from each other and kept absolutely separate as far as any electrical connection is concerned.

The chief advantage of the invention resides in the arm 13 and the relation thereof to the cylindrical body of the timer and the timer shaft, it being a simple matter to swing the retaining spring 5 out of engagement with the body of the distributor, 70 thus leaving the distributor free to be drawn out of engagement with the timer shaft and out of contact with the brush 31 of the contact arm 28.

The device hereinabove particularly described and herein fully illustrated is especially designed for use in connection with the engines now employed in Ford cars. 75

What I claim is:—

A distributor embodying a substantially 80 cylindrical body of insulating material provided with a radially extending arm having inclosed wire receiving passages, said body comprising a main section formed integrally with said arm and also formed with 85 a circular depression in one face thereof, another section seated in said depression and formed with an annular wire receiving channel in its inner face and also formed with an annular channel in its outer face, 90 and also formed with a circular depression in its outer face, a contact section seated in the last named section and having a circular series of contacts inset therein in line with the channel in the outer face of the 95 second section, and headed metal fasteners securing said contacts in place and having their heads arranged in the last named channel.

In testimony whereof I affix my signature in presence of two witnesses.

ROBERT S. NOAH.
